ROLL HEADING MACHINE

Arthur Wesley Lancaster and De Forest Charles Patmore, Orillia, Ontario, Canada, assignors, by direct and mesne assignments, of fifty per cent to Williams & Wilson Limited, Montreal, Quebec, and fifty per cent to E. Long Limited, Orillia, Ontario, Canada

Application September 14, 1951, Serial No. 246,548

7 Claims. (Cl. 53—64)

1

This invention relates to roll heading machines employed for gluing protecting and sealing heads, consisting of adhesively coated paper disks, to the wrapper covered ends of wrapped shipping rolls of newsprint or other paper to protect the ends of the rolls during shipment.

One object of the invention is the provision of a roll heading machine which is designed and operated to ensure application of the protecting heads to the ends of the roll in a uniform manner and in a minimum amount of time.

Another object is the provision of a roll heading machine designed and operated so that the advancement and retraction of the roll heading units and the ejection of the headed roll from the machine is accomplished with a minimum of manual labor.

Other objects, advantages and characteristic features of the invention will be apparent from the following detailed description of the accompanying drawings, in which—

Fig. 1 is a plan view of my improved roll heading machine.

Fig. 2 is a view, mainly in side elevation, of said machine. In this view parts of the base of the machine are broken away to show elements that would otherwise be concealed.

Fig. 3 is a vertical sectional view taken substantially along the section line 3—3 of Fig. 2.

Fig. 4 is a vertical sectional view taken substantially along the section line 4—4 of Fig. 2.

Fig. 5 is an elevational view of the right hand end of the machine shown in Figs. 1 and 2.

Fig. 6 is a sectional view taken substantially along the section line 6—6 of Fig. 2.

Fig. 7 is a fragmentary sectional view taken substantially along the section line 7—7 of Fig. 5.

Fig. 8 is a wiring diagram illustrating the electrical connections and control devices provided for operating electrically actuated valves through which pressure medium is routed to and from cylinder and piston devices which control the operation of the heading units and the roll ejecting means of the machine illustrated in the preceding figures.

Figs. 9 to 13 inclusive are wiring diagrams illustrating the sequential closing of the various circuits embodied in the complete wiring diagram shown in Fig. 8.

As shown in Figs. 1 to 7 inclusive, our improved heading machine comprises a hollow base member 5 supporting the roll heading units 6 and 7 and other parts of the machine hereinafter referred to.

Each of the roll heading units 6 and 7 com-

prises a hollow platen 8 carried by a travelling bracket 9 extending downwardly through a slot 10 in the top of frame 5. These platens are mounted so as to be self-aligning with the roll being headed. The lower end of each bracket 9 is slidably supported by a pair of guide plates 11 (Figs. 2 and 4) having their inner portions fitted in the bracket slots 12 and their outer portions secured to underlying supporting angles 13 welded or otherwise secured to the side members 14 of frame 5.

The travelling bracket 9 of heading unit 6 is attached to the piston rod 15 of a piston 16 working in a cylinder 17. The travelling bracket 9 of heading unit 7 is similarly attached to the piston rod 18 of a piston 19 working in a cylinder 20. The cylinders 17 and 20 are arranged in opposite end portions of frame 5 and are supported from the top portion of said frame by suitable supporting brackets 21.

A tiltable roll-supporting and ejecting platform 23 is arranged on frame 5 between the heading units 6 and 7 with the side edges of the platform projecting beyond the sides of the frame. One side of platform 23 and the adjacent side 14 of frame 5 are provided with interfitting pivot-forming elements 24 and 25 affording a horizontal axis about which the platform may be tilted from its normal horizontal roll-supporting position shown by full lines in Fig. 6 to an inclined roll-ejecting position indicated by dotted lines in said figure. Platform 23 is connected to the piston rod 28 of a platform operating piston 29 working in a cylinder 30 arranged in frame 5 directly below the platform. As shown to advantage in Fig. 6 platform 23 is shaped to provide an upper concave roll-supporting surface 31 on which the wrapped roll to be headed is supported and centered during the roll heading operation. As indicated by the full and dotted line showing of elements 24 and 25 in Fig. 6, the ejecting platform 23 may be said to move the roll either through the header or in the reverse direction.

The platens 8 of roll heading units 6 and 7 are made hollow so that these platens may be internally heated in conventional manner by electrical heating elements or other heating medium. Each platen is provided with a plurality of vacuum nozzles 32 connected, through pipes 33 and shut-off cocks 34, to a suitable vacuum line 35.

The wrapped roll of paper to be headed is placed on the roll-receiving platform 23 with the wrapper covered ends of the roll facing the roll heading platens 8. The protecting and sealing heads to be applied to the wrapped ends of

the roll consist of paper disks 37 (Fig. 2) having one side 38 coated with adhesive. The non-adhesive sides of these paper disks 37 are placed against the opposing working faces of the heading platens 8 and are held there by vacuum applied through the vacuum nozzles 32. The platens carrying the paper disks 37 are then advanced against the wrapped ends of the rolls to apply the paper disks thereto. This is accomplished, as diagrammatically illustrated in Fig. 8, by supplying air under pressure to the outer ends of cylinders 17 and 20 through solenoid-controlled valves 41 and 42 and simultaneously exhausting air from the inner ends of said cylinders through solenoid-controlled valves 43 and 44. After the adhesively coated sides of the paper disks have been applied to the wrapped ends of the rolls and the required heading pressure has been built up in cylinders 17 and 20, the valves 41, 42, 43 and 44 are permitted to resume their normally closed position and the pressure in the cylinders continues to hold the platens against the wrapped rolls for a sufficient time to ensure proper adhesion of the paper disks 37 to the portions of the wrapping covering the ends of the roll. After the platens 8 have been held under pressure against the wrapped ends of the roll for a sufficient period of time, air under pressure is supplied to the inner ends of cylinders 17 and 20 through solenoid-controlled valves 45 and 46 and is simultaneously exhausted from the outer ends of said cylinders through solenoid-controlled valves 47 and 48. This causes the platens 8 to be retracted to their normal starting position by outward movement of the pistons 16 and 19 and the attached platen carrying brackets 9 of the roll heading units 6 and 7. The valves 45, 46, 47 and 48 are permitted to close after the pistons 16 and 19 have travelled a short distance in a platen-retracting direction.

At a suitable time after retraction of the platens 8 from the wrapped ends of the roll air is supplied to the lower end of the tilting platform operating cylinder 30 through a 4-way solenoid-controlled valve 51 so that the piston 29 is raised to tilt the platform 23 to the roll ejecting position shown by dotted lines in Fig. 6. After ejection of the roll from the machine, valve 51 is operated to a position in which air is supplied to the upper end of cylinder 30 and is simultaneously exhausted from the lower end of the cylinder to move the piston 29 downwardly and thereby restore the platform 23 to its normal horizontal roll supporting position.

The valves 41 to 48 inclusive, controlling operation of the heading units 6 and 7 and the valve 51 controlling operation of the platform tilting piston are operated in proper sequence by the automatic opening and closing of suitable switches 53 and 54 through which the operating solenoids of the valves are connected across a source of electrical energy represented by the supply lines 55 and 56 in Fig. 8. The opening and closing of switches 53 and 54 is controlled by a timer 57 operated by a timer motor 58. The timer 57 may be of any suitable design. In the present instance and for illustrative purposes only the timer is represented as comprising a cam shaft 57a equipped with cams 59 controlling the opening and closing of a plurality of sets of timer contacts indicated, respectively, at 60, 61, 62 and 63. A drive connection between the timer shaft 57a and the timer driving motor 58 is established and disrupted by the engagement and

disengagement of an electrically actuated clutch which is diagrammatically represented by the clutch actuating coil 64. The timer 57, the driving motor 58, and the clutch operating coil 64 are put into operation, to start the roll heading operation, by momentary closure of a manually operable push button switch 65. The closure of this push button switch establishes circuit connections (Fig. 9) whereby the motor 58 and the clutch coil 64 are connected across the supply lines 55 and 56 to initiate operation of the timer. The initial operation of the timer 57 results in closure of the timer contact 60 to establish suitable circuit connections (Fig. 10) whereby the closed circuit condition of the motor 58 and the clutch coil 64 is maintained after the push button switch 65 is released and permitted to re-open. The timer contacts 60 remain closed until the roll heading and ejecting operations have been completed and the roll heading units and the roll ejecting piston have been returned to their normal starting positions. The timer contacts 60 are then re-opened to deenergize the motor 58 and the clutch operating coil 64.

The closure of timer contact 60 is followed by closure of the timer contacts 61. The closure of these last mentioned timer contacts establishes circuit connections (Fig. 11) whereby the operating coil 67 of the normally open valve controlling switch 53 is connected across the supply lines 55 and 56. The resulting closure of switch 53 connects the operating solenoids of the valves 41, 42, 43 and 44 across the supply lines 55 and 56 so that these valves are opened automatically to supply air to the outer ends of cylinders 17 and 20 and to simultaneously exhaust air from the inner ends of said cylinders to thereby cause the platens 8 to be advanced to their roll heading positions. After a predetermined time the contacts 61 of timer 57 are re-opened to deenergize the operating coil 67 of switch 53 and the resulting re-opening of switch 53 permits the valves 41, 42, 43 and 44 to close leaving the platens 8 pressed against the wrapped ends of the roll. After the platens 8 have been held against the ends of the roll for a suitable period, the timer contacts 62 are closed to establish circuit connections (Fig. 12) whereby the operating coil 88 of the previously mentioned normally open valve controlling switch 54 is connected across supply lines 55 and 56. The resulting closure of switch 54 connects the operating solenoid of valves 45, 46, 47 and 48 across supply lines 55 and 56 so that these valves are opened to supply air to the inner ends of the cylinders 17 and 20 and to simultaneously exhaust air from the outer ends of said cylinders. This results in the pistons 16 and 19 and the heading units 6 and 7 being moved outwardly and returned to their starting positions. After the heading units 6 and 7 have been moved outwardly a short distance by the pistons 16 and 19 to retract the platens 8 from the ends of the roll, the timer contacts 62 are permitted to re-open thus deenergizing the operating coil 88 of switch 54 so that the latter re-opens to deenergize the operating solenoids of the valves 45 to 48 inclusive, which thereupon return to their normally closed condition.

Following the re-opening of the timer contacts 62 the timer contacts 63 are closed to establish circuit connections (Fig. 13) whereby the operating solenoid of valve 51 is connected across the supply lines 55 and 56. Valve 51 is thus operated to a position in which air is supplied

to the lower end of the platform tilting cylinder 30 and is simultaneously exhausted from the upper end of said cylinder. The resulting upward movement of the platform tilting piston 29 tilts the platform 23 to the dotted line position shown in Fig. 6 and thus ejects the headed roll from the machine. Immediately after the roll ejecting operation the timer contacts 63 are re-opened and valve 51 returns to a position in which air is supplied to the upper end of cylinder 30 and is exhausted from the lower end of said cylinder to return the piston 29 and the roll ejecting platform 23 to their starting position. As this cycle of operation is completed the timer contacts 60 are re-opened so that the motor 58 and the clutch coil 64 are de-energized and remain so until another cycle of operation is initiated by re-closure of the manually operable bush button switch 65.

Provision is made for adjusting the operation of the machine to suit the length of the rolls to be headed. This is accomplished by providing two additional manually operable push button switches 91 and 92 electrically connected as shown in Figs. 8, 11 and 12. By the operation of these switches 91 and 92 it is possible to vary the extent of travel of the heading units 6 and 7 during both their working and return strokes. The closure of switch 91 energizes the operating coil 67 of switch 53 and closes the latter to connect the solenoid operated valves 41 to 44 inclusive across the supply lines 55 and 56 to effect a working stroke of the heading units 6 and 7. In this case the platens 8 will continue to approach each other as long as push button switch 91 is held in its circuit closing position. The extent to which the platens 8 of the heading units 6 and 7 are separated from each other by the return strokes of the heading units may be selectively controlled by closing the push button switch 92 and holding said switch closed until the platens have been separated a suitable distance with reference to the length of the roll to be headed. In this connection it will be noted that the closure of push button switch 92 connects the operating coil 88 of switch 54 across supply lines 55 and 56 so that switch 54 is thus closed to connect the valves 45 to 48 inclusive, across said supply lines to thereby operate the heading units 6 and 7 on their return stroke.

It may be noted here that the vacuum at the vacuum nozzles 32 of platens 8 is not sufficiently strong to pull the applied paper disks or heads 37 away from the wrapped ends of the roll during the return stroke of the platens. In this connection it will also be clear from the preceding description that the return stroke of the platens is not initiated until after a dwell period during which the adhesive bonding the disk 37 to the wrapped ends of the roll has set sufficiently to hold the disk to the rolls as the vacuum sides of the platens 8 are moved away from the contacting non-adhesive sides of the paper disks 37.

The invention also contemplates the provision of an emergency stop switch indicated at 94 in Fig. 8. If the machine is started accidentally or something goes wrong during the operating cycle the opening of switch 94 stops the machine and results in the component parts being returned to their starting positions.

Having thus described a preferred embodiment of our invention it will be understood that various modifications may be resorted to within the scope and spirit of the invention as defined by the appended claims.

The embodiments of the invention in which an exclusive property or privilege is claimed are defined as follows:

1. In a roll heading machine of the character described, a pair of roll heading units movable toward and away from each other, cylinder and piston devices connected to said units for moving the latter through their working and return strokes during a roll heading operation, automatic electrically actuated valves through which pressure medium is routed to and from said cylinder and piston devices to effect the aforesaid working and return strokes of said heading units, a source of electrical energy, a motor driven circuit-controlling timer operable to establish and disrupt circuit connections whereby said valves are periodically connected to and disconnected from said source of electrical energy in predetermined sequence, and a normally open manually operable switch through which control contacts of the timer and the motor terminals are connected across said source of electrical energy in the closed circuit position of said manually operable switch.
2. A roll heading machine as set forth in claim 1, including normally open timer contacts which are automatically closed at the commencement of operation of the timer to establish circuit connections whereby the closed circuit condition of the timer and the timer operating motor is maintained after re-opening of the manually operable switch.
3. A roll heading machine as set forth in claim 1, in which the timer is automatically clutched to the motor through the agency of an electrically actuated clutch including an operating coil which is connected across the source of energy through the circuit connections established by closure of said manually operable switch and which coil is maintained in its closed circuit condition subsequent to the opening of said manually operable switch by the circuit connections established by closure of said timer contacts.
4. A roll heading machine as set forth in claim 1, including additional normally open manually operable switches and circuit connections through which said electrically actuated valves are connectable across the source of electrical energy independently of the timer and the first mentioned manually operable switch.
5. In a roll heading machine of the character described, a pair of roll heading units movable toward and away from each other, cylinder and piston devices connected to said units, automatically controlled electrically actuated valves through which pressure medium is routed to and from said cylinder and piston devices to effect the working and return strokes of said heading units, a source of electrical energy, a motor driven electric timing mechanism including a plurality of sets of normally open contacts connected across said source, said sets of timer contacts being closed in predetermined sequence during a complete cycle of operation of the timer, normally open valve controlling switches through the agency of which groups of the electrically actuated valves are periodically connected and disconnected with said source of electrical energy in predetermined sequence, each of said valve operating switches including an operating coil connected across said source in series with one of the several sets of timer contacts, a normally open manually operable switch through which the timer operating motor is initially connected across the said source to commence operation of

the timer and means including one of the sets of timer contacts for maintaining the closed circuit condition of said motor after re-opening of said manually operable switch.

6. A roll heading machine as set forth in claim 5, including additional normally open manually operable switches and circuit connections through which said electrically actuated valves are connected across said source of electrical energy independently of said timer and said first mentioned manually operable switch.

7. In a roll heading machine of the character described, a stationary base frame, a pair of relatively movable roll heading units slidably supported by said frame, cylinder and piston devices connected to said units, a roll supporting and ejecting platform normally arranged in a horizontal position on a portion of the frame lying between said roll heading units, means pivotally connecting said platform to said frame to provide a horizontal pivotal axis about which the platform is swingable from its normal horizontal roll supporting position to an inclined roll ejecting position, a cylinder and piston device connected to said platform for swinging it about said horizontal axis, automatically controlled electrically actuated valves through which pressure medium is routed to and from said cylinder

and piston devices to effect the working and return strokes of said heading units and to effect the roll ejecting operation of said platform upon the completion of the roll heading operation and during the return strokes of said heading units, a source of electrical energy, a motor driven circuit controlling timer operable to establish and disrupt circuit connections whereby said valves are periodically connected to and disconnected from said source of electrical energy in predetermined sequence and a normally open manually operable switch through which control contacts of the timer and the motor terminals are connected across said source of energy in the closed circuit position of said manually operable switch.
